UNITED STATES PATENT OFFICE.

JOHN F. GRACE, OF KEARNEY, NEW JERSEY, ASSIGNOR TO HENRY R. WORTHINGTON,
A CORPORATION OF NEW JERSEY.

COUNTER-CURRENT CONDENSER.

1,183,867.

Specification of Letters Patent. Patented May 23, 1916.

Application filed November 15, 1913. Serial No. 801,169.

To all whom it may concern:

Be it known that I, JOHN F. GRACE, a citizen of the United States, residing at Kearney, county of Hudson, and State of New Jersey, have invented certain new and useful Improvements in Counter-Current Condensers, fully described and represented in the following specification and the accompanying drawings, forming a part of 5 the same.

This invention relates to jet condensers, and especially to counter current condensers, the especial object of the invention being to provide an improved construction by which 15 a more efficient action shall be secured, and which shall be simple, cheap and convenient in manufacture and use,—and further, to provide improved devices for cooling the air, and separating water therefrom, so that 20 the size of the dry vacuum pump may be reduced. While the invention is especially applicable to counter current condensers, many of the features are applicable also to jet condensers of other classes, and are thus 25 claimed.

For a full understanding of the invention, a detailed description of a counter current condenser embodying all the features of the same in their preferred form will now be 30 given in connection with the accompanying drawing forming a part of this specification, and the features forming the invention then specifically pointed out in the claims.

In the drawings, Figure 1 is a vertical, 35 central section of the condenser. Figs. 2, 3 and 4 are cross sections of the same, on respectively lines 2, 3 and 4 of Fig. 1.

Referring to the drawings, the condenser shell is preferably made in sections, as 40 shown, A being the inlet section having the steam exhaust inlet 10 at one side, B the condensing chamber section mounted on inlet section A, and having the injection or condensing water inlet 11, C the air outlet 45 chamber mounted on section B and having the air outlet 12, connected to the usual dry vacuum pump, and D the discharge outlet section below inlet section A, having the outlet 13 connected to barometric pipe or 50 discharge pump. These sections are preferably arranged, as shown, so that each lower section supports those above it, and the construction is preferably such, as described hereafter, that the condenser shell 55 and all the water trays and other parts with-

in the shell may be supported and properly held in place without the use of any bolts in contact with the circulating water, or at any place within the condensing chamber, so that only one metal, usually cast iron, is 60 in contact with the water, thus enabling the condenser to be used with water containing acids, without injury, and reducing largely the expense of manufacture and erection of the condenser, by avoiding the drilling and 65 tapping for bolts, and the fitting, bolting, etc., in erection.

Referring now to the interior construction of the condenser, 14 is a vertical sleeve within the casing opposite the water inlet 70 11, forming a condensing water chamber 15 between it and the outer shell, this sleeve 14 being seated on an interior shoulder 1 on casing section B, and preferably being provided with an annular series of openings 2, 75 through which small water jets are thrown inwardly. Within the sleeve 14, and receiving the condensing water flowing over the top edge of the sleeve, is the first water tray 16 provided with small jet openings 3 over its bottom, through which the water 80 flows downward. This tray 16 is supported by feet 4 set into notches in standards 5 on the next lower water tray 17, and is open at the center within the series of perforations 3 to receive the air pipe 18 extending upward and through which the air passes 85 to the air chamber C and air outlet 12. The second tray 17 is provided with perforations 6 in its bottom, which preferably are 90 larger than perforations 3, and the water flows in jets through these perforations and off the bottom of the tray 17 between the standards 5, into the third tray 19, which is provided with bottom perforations 7, 95 preferably larger than the perforations 6. This tray 19 is hung inside the casing section B, by ears 20 on the tray, having vertical ribs 8 on their under side which extend downward between inwardly projecting lugs 9 upon the casing, so that the tray is held in proper circumferential position and supported by the lugs. This third tray 19 also supports the second tray 17, the latter 100 having feet 21 resting on the bottom of tray 19.

Below tray 19 is the fourth tray, this tray being formed by inner flange 22 on the inlet casing A and short vertical cylinder 23 set into the opening within the flange to 110

form the inner wall of the tray and supported by ears 26 on the outside of the cylinder, which rest upon the said flange 22. The opening for the cylinder is not concentric 5 with the casing, but arranged at one side of the center, away from the steam inlet 10, thus securing a better distribution of the steam by carrying the steam over farther from the inlet toward the opposite wall of 10 the casing. The cylinder 23 is provided on the side away from the steam inlet with a curved lip 24 extending partially over the top of the cylinder and having a notched vertical edge 25, over which the water flows 15 to the central opening from the side away from steam inlet, so that the water does not pass over the edge of the tray in normal operation, except through the notches, thus leaving a freer passage for the steam upward 20 through the open cylinder in counter current to the water spray dropping from openings 7 in tray 19. The steam inlet 10 and inlet casing A may be turned in any direction desired relatively to the casing section 25 B, for convenience in erecting, and the cylinder 23, with the notched edge 25 on the side of the condenser away from inlet 10, is held in position by vertical ribs 27 on the top of one of the supporting lugs 26 between 30 one or the other of the pairs of lugs 28 on the inner side of the casing section B. The cylinder is preferably smaller than the opening in flange 22 and held in position in the opening by ribs 29 on the outside of the cylinder, so that a narrow water space is provided 35 around the cylinder through which water flows downward. The sheet of water flowing downward through this space on the rear side of the condenser is broken up into jets and thrown forward by baffles 30, but the sheet of water at the front or inlet side of the condenser is preferably continuous or nearly so to direct the steam around the condenser to the free entry space at the 40 back and secure proper steam distribution. 45

Referring now to the air cooling and separating devices, the air pipe 18 is supported by a flange on the bottom of tray 16, and in turn connects at its upper end with the 50 center of separator E, the air pipe 18 connecting with curved radial passages 31 in the separator, by which a centrifugal or cyclonic action is secured, acting to separate the water from the air, the water then 55 flowing downward into tray 16, and the air passing upward through chamber C and air pipe 12 to the dry vacuum pump. The centrifugal air separator is supported at its edges by resting on interior shoulders 32 60 on the upper end of casing section B.

A spray pipe is preferably used for spraying water into the air in pipe 18 below the separator E, spray pipe 33 being shown for this purpose, the lower end of which is 65 formed in any suitable manner to secure the

spraying action desired. In cases in which the condensing water is of sufficiently low temperature, this spray pipe may be supplied with condensing water or may be omitted, but the independent spray pipe construction shown also enables cold water to be brought in from another source for cooling the air, so that water of any desired temperature may be used for this purpose, irrespective of the temperature of the condensing water. This feature is important, in that it enables a smaller dry vacuum pump to be used. 70 75

The invention provides a very efficient counter current condenser, by which the desired condensing action can be secured with a smaller condenser and a less quantity of condensing water than previously used, and which is cheap of manufacture, and simple and convenient in construction and repair. 80 85 The gradually increasing size of the openings in the bottoms of the trays, with the smaller openings above, is important in that any foreign matter coming into the condenser of such size as to pass through the 90 first openings, passes readily through the rest of the trays to the discharge, and the larger material is collected in the top tray, from which it may readily be removed through the handhole 40 shown. An important feature also is the fact that the excess water flowing from the upper pans passes directly downward to the bottom pan at the side or in the outer portion of the condensing chamber, so as not to close the 95 spaces between the pans or choke the passage to the air suction, as is liable to happen in other counter current jet condensers in which the water is delivered in all quantities in a serial flow from pan to pan. This 100 condenser also secures the advantage of using the central space, with a heavy rainfall therein through the slots in the pans, so that the water is finely divided through the 105 entire condenser. The water spray arrangement opposite the exhaust inlet also provides for proper distribution of steam and avoids the tendency to deadness, the steam being directed around the condenser and having a free entry at the rear side, so as to 110 be well distributed throughout the condenser. 115

It will be understood that the invention is not limited to the exact form or arrangement of parts shown, but that the features 120 forming the invention, as defined by the claims, may be embodied in different constructions.

What is claimed is:

1. In a counter current condenser, a plurality of water trays arranged one above the other, said trays being arranged for the discharge of overflow from the edges of the trays outward to the condenser wall and downward outside the lower trays and pro- 125 130 135

vided with spray openings in the bottoms of the trays, the spray openings of the successive trays increasing in size from the upper tray downward, in combination with a 5 condensing water supply to the upper tray.

2. In a counter current condenser, a plurality of water trays arranged one above the other and provided with spray openings in the bottoms of the trays, said trays being 10 arranged for the discharge of overflow from the edges of the trays outward to the condenser wall and downward outside the lower trays, to leave the central part of the condenser open for the steam and water sprays.

15 3. In a counter current condenser comprising a shell, an inlet shell section having a side steam inlet and a top flange provided with an opening for the passage of steam and water, in combination with a cylinder 20 in said opening forming with the flange and shell a water tray and having the tray wall on one side formed to divide water flowing over the edge of the cylinder into separate streams, said cylinder being positioned on 25 the inlet section to bring the divided stream wall onto the side of the condenser away from the steam inlet in different positions of the inlet section.

4. In a condenser comprising a shell, an 30 inlet shell section having a side steam inlet and a top flange provided with an opening for the passage of steam and water, said opening being eccentric to the section and on a side away from the inlet, in combination 35 with a cylinder in said opening forming with the flange and shell a water tray and having the tray wall on one side formed to divide water flowing over the edge of the cylinder into separate streams, said cylinder 40 being positioned on the inlet section to bring the divided stream wall to the side of the condenser away from the steam inlet in different positions of the inlet section.

5. In a condenser comprising a shell, an 45 inlet shell section having a side steam inlet and a top flange provided with an opening for the passage of steam and water, in combination with a cylinder in said opening forming with the flange and shell a water 50 tray and having the tray wall on one side formed to divide water flowing over the edge of the cylinder into separate streams, said cylinder being positioned on the inlet section to bring the divided stream wall 55 onto the side of the condenser away from the steam inlet in different positions of the inlet section, and a substantially continuous water passage in front of the steam inlet to provide a substantially continuous sheet of 60 water for directing the entering steam around the inlet section of the condenser.

6. In a condenser having a steam inlet at 65 the side, water spraying devices above the steam inlet arranged to produce a substantially continuous sheet of water in front of

the steam inlet to direct the stream around the condenser, and divided streams for admission of the steam to the condenser space away from in front of the steam inlet.

7. In combination with condensing chamber section B, of steam inlet section A having side steam inlet 10 and top flange 22 provided with a top opening, of cylinder 23 in said opening forming with the condensing chamber section and flange a water tray 70 and through which the steam passes upward and the water spray downward, and divided wall 25 on the side of the cylinder away from the inlet 10 for forming separated streams of water at the rear side of the condenser between which the steam passes.

8. In combination with condensing chamber B, of steam inlet section A having side steam inlet 10 and top flange 22 provided with a top opening, of cylinder 23 in said 80 opening forming with the condensing chamber section and flange a water tray and through which the steam passes upward and the water spray downward, and divided wall 25 on the side of the cylinder away from the inlet 10 for forming separated streams of water at the rear side of the condenser between which the steam passes, said cylinder 90 being separated from the flange in front of the steam inlet to provide a substantially continuous water space through which a sheet of water passes down in front of the steam inlet to direct the steam around the condenser.

9. A counter-current condenser having a 100 plurality of water-trays arranged one above the other and provided with spray openings in the bottoms of the trays, and with the top tray and a lower tray or trays separated from the wall of the condenser to provide 105 space for the overflow from the upper tray or trays to pass between the lower tray or trays and the condenser wall.

10. A counter-current condenser having a 110 plurality of water-trays arranged one above the other and provided with spray openings in the bottoms of the trays, and with the top and intermediate trays separated from the wall of the condenser to provide space for the overflow from the upper tray or trays 115 to pass between the intermediate trays and the condenser wall directly to the bottom tray.

11. A counter-current condenser having a 120 plurality of water-trays arranged one above the other and provided with spray openings in the bottoms of the trays, and with the top and intermediate trays separated from the wall of the condenser to provide space for the overflow from the upper tray or trays 125 to pass between the intermediate trays and the condenser wall directly to the bottom tray, and means whereby overflow from the bottom tray produces a substantially continuous sheet of water in front of the steam 130

inlet, and divided streams of water on the side away from the steam inlet.

12. In a counter current condenser, the combination with a condensing shell section having a side condensing water inlet and an interior shoulder below said inlet, of a cylinder supported by said shoulder and arranged to form with said shell a reservoir, and a plurality of water trays arranged one above the other within and extending below said cylinder, said trays supported from said shoulder by the bottom tray, and provided with spray openings in the bottoms of said trays, the spray openings of the successive trays increasing in size from the upper tray downward.

13. In a counter current condenser, the combination with a plurality of water trays arranged one above the other and provided with spray openings in the bottoms of said trays, of a centrifugal air separator in the upper portion of said condenser and means

connecting said separator with the space between the first and second of said trays.

14. In a counter current condenser, the combination with a plurality of water trays arranged one above the other and provided with spray openings in the bottoms of said trays, of a centrifugal air separator in the upper portion of said condenser having an air pipe connecting said separator with the space between the two top trays of said plurality, and a spray pipe within said air pipe and independent of the condensing water connection for spraying water into the air before its passage to the separator.

In testimony whereof, I have hereunto set my hand, in the presence of two subscribing witnesses.

JOHN F. GRACE.
